(**) Term: **14 Years**

(57) **CLAIM**

The ornamental design of a touch pad for destination selection controller, as shown and described.

(21) Appl. No.: **29/429,858**
(22) Filed: **Aug. 17, 2012**

DESCRIPTION

(30) **Foreign Application Priority Data**

Feb. 17, 2012 (KR) 30-2012-0007265
FIG. 1 is a front perspective view of a touch pad for destination selection controller showing our ornamental design;
(51) **LOC (10) Cl.** **10-05**
FIG. 2 is a front elevational view thereof;
(52) **U.S. Cl.** **D10/108**
USPC D10/108
FIG. 3 is a back elevational view thereof;
(58) **Field of Classification Search**
USPC D10/108; D21/812; 340/474; 200/520,
200/341; D13/158, 171, 174; 187/389-391,
187/396-397, 380, 390
FIG. 4 is a left elevational view thereof;
FIG. 5 is a right elevational view thereof;
FIG. 6 is a top plan view thereof;
FIG. 7 is a bottom plan view thereof;
FIG. 8 is front elevational view thereof, mounted to a pedestal;
FIG. 9 is a right elevation view thereof, mounted to a pedestal;
and,
FIG. 10 is a back elevational view thereof mounted on a pedestal.

The broken line representations in the figures, such as the pedestal, are for the purpose of illustration only, and form no part of the claimed invention.
